US00D941773S

(12) **United States Design Patent** (10) Patent No.: **US D941,773 S**
Mi (45) Date of Patent: ** Jan. 25, 2022

(54) **POWER STRIP**

(71) Applicant: **CHIZHOU FENGAN ELECTRONICS TECHNOLOGY CO., LTD**, Chizhou (CN)

(72) Inventor: **Xueyan Mi**, Chizhou (CN)

(73) Assignee: **CHIZHOU FENGAN ELECTRONICS TECHNOLOGY CO., LTD**, Chizhou (CN)

(**) Term: **15 Years**

(21) Appl. No.: **29/777,945**

(22) Filed: **Apr. 9, 2021**

(51) LOC (13) Cl. **13-03**

(52) U.S. Cl.

USPC **D13/137.4**

(58) **Field of Classification Search**

CLAIM

The ornamental design for a power strip, as shown and described.

DESCRIPTION

FIG. 1 is a perspective view of a power strip showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the power strip where the power strip is in a configuration of use.

The broken lines in the drawings depict portions of the power strip that form no part of the claimed design.

1 Claim, 9 Drawing Sheets
